US00D515441S

(12) **United States Design Patent** (10) Patent No.: **US D515,441 S**
Shindo (45) Date of Patent: **** Feb. 21, 2006**

(54) **COMBINED MONITOR AND LOCATING SYSTEM**

(75) Inventor: **Koji Shindo**, Tokyo (JP)

(73) Assignee: **Sony Corporation**, Tokyo (JP)

(**) Term: **14 Years**

(21) Appl. No.: **29/196,080**

(22) Filed: **Dec. 23, 2003**

(51) **LOC (8) Cl. 10-04**

(52) **U.S. Cl. D10/65; D14/346**

(58) **Field of Classification Search** D14/231,
D14/230, 252, 253, 137, 188, 240, 118, 346;
D16/135; D10/65; 701/200; 455/130; 375/147;
725/46
